UNITED STATES PATENT OFFICE.

LEO J. BINDER, OF SPOKANE, WASHINGTON.

GRATE.

Application filed March 10, 1926. Serial No. 93,690.

This invention relates to grates for boiler and other furnaces, and particularly grate bar units of that type comprising a support and grate sections removably disposed thereon.

The primary object of the present invention is to provide a novel form of end or cap section which is readily separable from and attachable to the extremity of a support 10 having a plurality of intermediate grate sections thereon and cooperating with the latter sections and the grate unit as a whole to produce means for stabilizing the support of the grate unit and embodying structural means 15 for conveniently connecting and disconnecting the end or cap section relatively to the support extremity, either in a grate unit organization having a fixed position or in a similar unit having a rocking structure and 20 mounting.

A further object of the invention is to provide an end or cap section removably applicable to the extremity of a support, and not only having structural means to facilitate application and removal of the said 25 end or cap section relatively to the support extremity, but also comprising grate members or inwardly extending grate portions of varying lengths, to compensate for differences in the lengths of grate supports and 30 to complete the grate unit covering the opposite extremities relatively to a predetermined number of intermediate grate sections held on the support between end or cap sections.

With the foregoing and other objects and advantages in view, the invention consists in the preferred construction and arrangement of the several parts which will be more 40 fully hereinafter described and claimed.

In the drawings:

Fig. 1 is a perspective view of a grate bar unit comprising a support, removable intermediate grate sections, and end or cap sections embodying the features of the invention.

Fig. 2 is a central longitudinal vertical section of the grate unit shown by Fig. 1 broken through at different parts and the intermediate grate sections omitted, and particularly illustrating the improved end or cap sections, one of which is fully applied at one extremity of the support and the other partially assembled in relation to the opposite extremity of the support.

Fig. 3 is an inner end elevation of the improved end or cap section.

Fig. 4 is a perspective view of a portion of the support constructed to receive the improved end or cap section.

Figs. 5 and 6 respectively illustrate a side elevation and bottom plan view of the improved end or cap section and showing structural rocker accessories in connection therewith.

The numeral 5 designates a grate section support, which may vary in length in accordance with the length of the complete grate organization of which it forms a part, there being in practice a requisite number of these 70 grate section supports installed in a grate organization in accordance with the width of the latter. Each grate section support comprises parallel sides 6 of similar construction and dimensions and having the greatest 75 width or vertical extent at the center, and from the central portion thereof tapering towards the opposite ends, as is well understood in grate section construction. At the center of the support 5, between the sides 6 80 and the opposite ends, are connecting webs or bridge strips 7 and 8, the end webs 8 forming terminal closures for the support and extending the full vertical extent of the opposite extremities of the sides 6 of the support. The webs or bridge strips 7 and 8 are integrally formed with the sides 6 and the upper edges of the sides 6 and the corresponding edges of the webs or terminal walls 8 are inwardly beveled as at 9 and 10, to provide 85 retention seating means for intermediate grate sections 11 and 12, there being three of these sections shown; or one center section and two outer sections having end jointure with relation to the opposite ends 90 of the said center section. These grate sections 11 and 12 are of uniform length and width as specified in my copending application, Serial No. 88,614, filed Feb. 16, 1926.

The intermediate sections 11 and 12 are also 100 formed with suitably shaped openings 13, which, as shown, extend longitudinally of the said section but may be varied in their contour. The opposite ends of all of the intermediate sections 11 and 12 are similarly 105 constructed, or have centrally located engaging shoulders 14, which serve to prevent the said intermediate sections from shifting laterally out of place with relation to the support 5. The intermediate sections 11 and 12 110

are also provided with projecting transverse short ribs 15 at opposite sides to engage corresponding ribs formed as a part of adjacent intermediate sections, and thereby enable the entire grate surface to be provided with regular openings therethrough similar to the openings 13. The support 6 at opposite ends has outwardly projecting bearing extensions or short arms 15, which are reduced towards their free ends and preferably curved or rounded and provided with openings 16, one in each bearing extension or arm. Each of the end webs or terminal walls 8 has a lower transverse slot 17 formed therein and preferably of rectangular contour.

The essential feature of the present invention, as heretofore indicated, consists of a novel form of end or cap section 18 having an outwardly projecting body 19 with a flat top and a depending, outwardly inclined flange 20, a socket 21 opening through the bottom of the said body for convenience in applying the end or cap section to a suitable engaging or supporting means at opposite sides of the furnace, said means usually being applied on a ledge or otherwise disposed and held in stable position at opposite ends of a furnace enclosure or wall. At an intermediate point the end or cap section 18 has a substantially flat, vertically depending flange 22 terminating in an inwardly projecting angular lip 23, the said lip having a depending terminal 24 which is disposed adjacent the inner side of the lower portion of the web or wall 8 when the end cap or section is applied in operative position to the support. From the body 19 and projecting inwardly beyond the flange 22 is a grate member or section 25, having an inner end 26 shaped similarly to the outer ends of the grate sections 12 of the intermediate group of sections, the said end 26 having a central shoulder 14 to engage and abut against the corresponding shoulders 14 at the outer ends of the sections 12. The grate member or section 25 is also provided with a plurality of openings 27, of suitable shape, which extend therethrough and permit ashes and other products of combustion that may be deposited on the said member or grate section 25 to fall within the support to the ash pit below. On opposite sides of the vertical center of the flange 22 rectangular slots 28 are formed and are of such dimensions as to snugly receive the extensions or arms 15 at the opposite ends of the support 5, and when the said extensions or arms 15 are inserted through the slots 28 the free ends of said extensions or arms project outwardly beyond the outer sides of the flanges 22 depending from the end or cap sections, and a pin or bolt 29 may be inserted through the openings 16 to prevent the end or cap sections from being displaced and

thereby effect a solid grate assemblage. This coupling bolt or pin 29 need not necessarily be used under conditions where it is found that the extensions or arms 15 are sufficient to maintain a positive assemblage of the end or cap sections with the opposite ends of the support, such pins or bolts being used only in an emergency to lock the end or cap sections to the support, so that these parts may be handled as a unit to refill an open space in the furnace caused by a broken grate or one that has fallen from its bearings during operation thereof. The slots 17 in the end bridges or walls 8 are of such vertical extent or width as to permit the angular lips or hook members 23 to be readily inserted therethrough and moved outwardly therefrom.

The grate structure thus far described embodies an end or cap section adapted for use with a stationary grate. In Figs. 5 and 6 means are shown provided in connection with the same form of end or cap section to adapt the latter for a grate construction of the rocker or shaker type, and the addition necessary is in the form of an arm 30 extending from the center of each flange 22 and having an outwardly projecting trunnion stud 31, which is located at such distance below each angular lip 23 as to not in the least interfere with the latter in its association or dissociation with relation to the end webs or walls 8 of the support. The end or cap section shown by Figs. 5 and 6 is in all respects similar in general construction to that heretofore described with the exception that the outwardly inclined flange 20 is replaced by a vertical flange 32, a trunnion 33 projecting outwardly from the center of the outer terminal end of the section 18 for engagement with a suitable apertured or recessed means located at opposite ends of the grate enclosure, or adjacent the end walls of the latter, as will be readily understood. By the addition of the arm 30 and the stud 31 and trunnion 33, it will be seen that the improved end or cap section in its general organization, or including all of the essential features common to both forms, may practically serve in connection with a stationary grate unit or a rocker or shaker unit.

The assemblage of the improved end or cap sections 18 as hereinbefore described and the webs or walls of the support 5 is a very simple operation, it only being necessary to dispose each end or cap section at an angle as shown by Fig. 2, to permit the depending hook member 23 to pass through the slot 17, and then gradually raise or bring the upper or top portion of the end or cap section into horizontal position and push inwardly on the same to cause complete engagement of the angular lip member with the slot and the insertion of the extensions or arms 15 through the slots 28. After the end or cap

sections have thus been applied, the extensions or arms 15 may be connected by a cross pin or bolt 29, as hereinbefore described, or in some instances this cross pin or bolt may 5 be omitted. Should the grate end or cap sections break, the angular lips 23 will serve to hold up the said sections and prevent the same from falling into the ash pit, in view of the fact that the horizontal part 23^a of 10 each angular lip would then contact with the top walls of the slots 17 and suspend the support until repair could be made. Furthermore, in the event of fracture or breakage of the angular lips or hooks 23 and a consequent 15 failure of the said lip or hook to hold up the support, the latter would then be held normally in place by the extensions or arms 15 until suitable repairs could be made. It will also be seen from the foregoing that the 20 flange 22 of each end or cap section serves as a hanger with a lower hook means of such shape as not only to insure a positive association of the end or cap sections with the end of the support, but also to hold up the 25 support in the event of breakage, and the extensions or arms 15 contribute to the upholding of the support by engaging the slots 28 in the flange of the hanger.

The improved end or cap section as heretofore described also efficiently operates as an enclosure for the end of the support to which it is applied and protects the said support end against any intense heat and preserves and renders it more durable. Furthermore, 30 it is intended to standardize the dimensions of the end or cap sections and have the inwardly projecting grate member or section 35 vary in length to compensate for differences in the lengths of supports and fully 40 cover the opposite extremities of the support and permit a maintenance of uniformity of length of the intermediate sections comprising the center and outer sections 11 and 12, as fully explained in my copending application 45 hereinbefore specified. The improved end or cap sections are also interchangeable and one of the same standardized dimensions may be readily substituted for another of similar dimensions, it being proposed to 50 carry standardized end or cap sections embodying the features of the present invention in stock and readily obtainable for replacement or substitute purposes.

The essential features of the present invention also contemplate the provision of a support for a grate unit having an integral construction and comprising end walls with slots in the lower portions thereof together with outwardly projecting bearing extensions or short arms 15 adapted to have associated therewith an end or cap section with relative structural features, to permit enclosing engagement thereof with the end of the support, and further, to provide an end 60 or cap section having structural features

which will permit ready assemblage and detachment thereof relatively to a support embodied in a grate unit, and to effect an obstruction to the falling or breaking down of any part of the end or cap section and also 70 the support into the ash pit below, there being a cooperative operation of the separably joined parts of the support and end or cap sections.

The structure in this application materially differs from that disclosed by my copending application Serial No. 93,691, filed March 10, 1926, by having the projecting angular lip 23 formed as a part of the end section, or provided at the lower terminal of 75 the vertically depending flange 22 of said section and movable into and becoming interlocked with the opening 17 in the end bridge strip 8, the depending terminal 24 of the lip 23 being located inside of the said bridge 80 strip when the end section is applied. In application Serial No. 93,691 the bridge strip carries the angular lip and the latter passes through a slot formed in the flange of the 85 end section. 90

What is claimed as new is:

1. A grate unit comprising a support with end walls integrally formed therewith and having slots extending through the lower portions thereof above the lower terminals 95 of the said walls, grate sections mounted on the support, and end cap sections fitting over and enclosing the ends of the support, the ends of the support having upper outwardly projecting arms at opposite sides above the 100 slot of each wall and each enclosing end cap section having an intermediate depending flange terminating at its lower end in a right angle projecting lip with a depending terminal of hook form to pass through the slot of 105 the adjacent wall of the support and bear against the lower portion of said wall below the slot therein, the upper portion of the flange of the cap section being provided with slots on opposite sides of the center to receive the projections of the support. 110

2. A grate unit comprising a support with side members connected at each end by a flat wall extending fully to the lower edges of the side members and having a single opening therethrough at its lower portion and said wall also provided at the upper portion with a pair of outwardly projecting parallel arms, and an end cap section applied against and partially enclosing the adjacent 115 end of the support and having an intermediate depending flange with a lower right-angled inwardly projecting retaining member terminating in a downwardly extending hook to pass through the opening in the adjacent end wall so that the hook terminal 120 will bear against the inner side of the wall below the said opening, the depending flange of the cap also being formed with upper spaced openings therethrough through which 125 130

project the upper arms of the support, whereby the support is sustained in its normal outward position through the cap sections and the latter connected to opposite 5. ends of the support.

3. A grate unit comprising a support with parallel side members having closing end walls provided with openings, one in each 10 near the lower edge of said walls and also having arms projecting outwardly in parallel relation and coincident with the side members of the support, and end cap sections partially extending over and enclosing the opposite ends of the support and each 15 provided with an intermediate depending flange having the lower end directed inwardly at a right-angle and terminating in a

downward projection to enter the opening in the adjacent wall of the support so that the 20 downwardly projecting terminal of the flange will bear against the inner lower side portion of the said wall, the flange of the end cap also having upper openings in each 25 side of the center through which pass the arms of the support, the flange of the cap section also having means below the angular inwardly projecting portion of the flange for the application of means for shaking the grate unit, the latter being provided between the end sections with removable grate sec- 30 tions on the top portion thereof.

In testimony whereof I have hereunto set my hand.

LEO J. BINDER.
